UNITED STATES PATENT OFFICE.

FREDERICK W. H. COLLETT, OF CAMBRIDGE, MASSACHUSETTS, ASSIGNOR, BY MESNE ASSIGNMENTS, TO SIMMONS COMPANY, OF KENOSHA, WISCONSIN, A CORPORATION OF DELAWARE.

MATTRESS-SIDE-STITCHING MACHINE.

Application filed March 31, 1921. Serial No. 457,194.

To all whom it may concern:

Be it known that I, FREDERICK W. H. COLLETT, a citizen of the United States, residing in Cambridge, in the county of Middlesex and State of Massachusetts, have invented an Improvement in Mattress-Side-Stitching Machines, of which the following description, in connection with the accompanying drawings, is a specification, like reference characters on the drawings designating like parts.

This invention relates to a mattress side stitching machine for producing what is commonly known as a roll edge on a mattress.

The character of the product of the machine is the same as that of the machine forming the subject of U. S. Letters Patent No. 1,342,423 granted to my assignee on the 20th day of June, A. D. 1920, to which reference may be had to facilitate an understanding of the present invention, which may be regarded as an improvement thereon.

The present invention relates mainly to the feed mechanism which operates to present the mattress to the twine operating instrumentalities of the portion of the machine called in that patent the stitcher, and 30 to feed or advance the mattress after each cycle of operations of the stitcher to the proper position for the next such cycle.

In an embodiment of the present invention the stitcher may be the same as shown in said prior patent, as the stitch forming instrumentalities form no part of the invention except as a unitary element in combination with the novel mattress supporting and feeding mechanism.

In the machine forming the subject of the present invention the stitcher is stationary and the mattress is supported on a table located in proper relation to the stitcher and having a smooth top on which the mattress slides easily, and the invention consists in part in the combination with the stitcher and table of a system of belts and actuating mechanism therefor which facilitate, or contribute to the movement of the mattress on the table in the manipulation by the operator and in the automatic feed movement which in co-operation with the stitcher effects the proper spacing of the

individual stitches or knotted loops which make the desired roll edge seam. 55

Another portion of the invention consists in the combination with the table and stitcher of a mechanism which collectively constitutes the feed mechanism proper, and comprises a pair of clamp members or jaws, one above and the other below the body of the mattress, and actuating mechanism therefor, timed relative to the operation of the stitcher mechanism, by which, in the intervals between the stitch forming cycles, the said jaws are moved further apart to disengage or release the mattress, are then moved along over the mattress in the direction opposite to the feed, are then moved towards one another to clamp and compress the mattress between them, and then are moved in the direction of the feed, carrying the mattress with them the distance desired between the individual knotted loop stitches, commonly about two inches, which completes a cycle of feed operations, at the end of which the feed mechanism remains holding the mattress clamped while the next stitch is made by the stitcher. 75

Another portion of the invention consists in the combination with the components above referred to of a pair of guides, shown as rails or bars which are pressed yieldingly against the top and bottom surfaces of the mattress on lines of considerable length 85 parallel to the side being sewn, which contribute to the guidance of the mattress in the feed movement, and to the holding of the mattress in the stitching operation.

Another portion of the invention comprises certain awls and actuating mechanism therefor, timed relative to the feed, by which the said awls are caused to penetrate the side of the mattress and then to have a pivotal movement, one towards one, and the other towards the other corner of the mattress about to be stitched, the purpose being to square the side of the mattress, if as sometimes is the case, it is somewhat distorted, and to insure that the stuffing fills 100 both corners before they arrive at the point at which the knotted loop stitches are formed in both corners at the same operation.

The invention further consists in various 105 combinations of mechanism and features of

construction and arrangement which will appear in the description of the embodiment of the invention illustrated in the accompanying drawings, in which:—

5 Fig. 1, is a plan view, diagrammatic in character, showing the general relation to one another of the parts mainly concerned in the support and feed of the mattress, the stitcher being omitted;

10 Fig. 2, a sectional view showing the principal part of the mechanism in elevation, as viewed looking from the left towards the right in Fig. 1;

15 Fig. 3, a similar view, but looking from the opposite end, Fig. 3, being on a larger scale than Fig. 2, and Fig. 1, being on a smaller scale;

20 Fig. 4, an enlarged detail view of the feed mechanism and mattress guides as seen from the rear, or looking from the middle or back of the table;

Fig. 5, a detail of the feed jaws or clamp;

25 Fig. 6, an enlarged detail, viewed as in Fig. 2, of the mattress squaring awls and their actuating mechanism;

Fig. 7, a plan thereof but with some of the parts in a different position;

Fig. 8, a detail of one of the awls and its stock and cam arm;

30 Fig. 9, a detail of the mechanism for actuating the mattress impelling belts; and

Fig. 10 and 11, sectional details illustrating the operation of the regulating awls.

35 The mattress supporting table 2, has a recess 22, in the side where the feeding and stitching mechanism act upon the mattress 200, as best shown in Figs. 1 and 2, thus affording the working instrumentalities access to the lower surface of the mattress.

40 The specific construction of the stitcher or mechanism that acts on the mattress and twine or thread in making the stitches of the seam constitutes no part of the present invention except as a unitary element of some of the novel combinations, and said stitcher may be of the construction set forth in my prior Patent No. 1,342,423 before referred to, a sufficient portion of the mechanism being herein shown to indicate its combinative relation to the other elements of the present machine.

45 Such portion of the stitcher is best shown in Fig. 2, in which the needles are marked 100, and the shaft on which the hollow cam shaft of the stitcher is mounted is marked 20, and is driven by a power shaft 21, (see Figs. 1 and 3) suitably connected therewith as by a worm and worm gear.

50 The feed mechanism proper by which the mattress is advanced between successive cycles of operation of the stitcher comprises a pair of jaws or clamp members 3, each pivotally connected at 4 with an arm 5 fixed to a rock-shaft, marked 6 for the upper jaw,

65 and 7 for the lower, said rock-shafts being

70 journaled in the main supporting frame of the machine as best shown at 8 in Fig. 3.

The jaws 3 have long and broad mattress engaging faces which are shown as provided with cross ribs of rubber or clinging material and they thus compress a considerable portion of the mattress between them as is well shown in Figs. 2 and 4, and by their pivotal movement on the joints at 4 they may be moved towards and from one another to clamp the mattress and to release it, and they are moved forward in the direction of the feed when closed upon the mattress, and backward when opened, by the action of the arms 5 when the rock-shafts 6, 7, are oscillated by the actuating mechanism which will now be described.

75 The feed jaws 3 are actuated in all their movements by a cam 10, on the main shaft 20, said cam acting on a roller 12 on a link or bar 13 connected at its ends with crank arms 14 on the rock-shafts 6, 7, so that the upward movement of the bar 13 causes the forward feed movement of the jaws 3, in the direction of the arrow in Fig. 4, and the downward movement produces the backward movement of said feed clamp jaws preparatory for the next forward movement in which the mattress is advanced to the position for the next stitch.

80 The same cam surface acts upon another roller 15 on a lever 16 pivoted at 17 on the frame, and provided near its free end with a pawl 18 adapted to engage with a shoulder 19 on a vertically movable slide bar 24, connected near its upper end by a universal joint with a connecting rod 25, which is connected at its other end with one end of a lever 26 fulcrumed on a block 27.

85 The other end of said lever 26 is connected by a rod 28 with the upper jaw of the feed clamp as best shown in Fig. 4, and the ball and socket or universal joint connections with said connecting rod 28 accommodate the feed movements of the clamp as well as the pivotal movement of the jaw 3 at 4 and the rocking movement of the lever 26.

90 The fulcrum block 27 is capable of movement on an upright 30 forming a part of the main frame and is pressed against a stop and guide block 31, fixed upon said upright, by a spring 32 which may yield after the jaw comes to its bearing on the mattress, so as not to put excessive pressure on the mattress. The block 31 is provided with a steady pin 33 entering a guide passage in the fulcrum block 27 which prevents said fulcrum block from turning on the upright 30 while permitting it to rise in overcoming the force of the spring 32 in case the mattress is not sufficiently compressible to permit the full movement of the feed clamp jaw.

95 The lower end of the slide bar 24 acts through the intervention of a spring 320

(see Figs. 3 and 4) on a lever 260 fulcrumed at 270 on the main frame and connected at its other end by rod 280 with the lower clamp jaw 3 so that the upward movement of the slide bar 24 which causes the downward movement of the upper feed clamp jaw also causes the upward movement of the lower jaw and closes the clamp on the mattress with a yielding pressure owing to the action of the springs 32, 320, so that the stuffing of the mattress is not unduly compressed. The connections of the rod 280 with the lever 260 and with the lower clamp jaw are by universal (ball and socket) joints, thus accommodating the various movements of the lower feed clamp jaw.

By having the clamp opening and closing member such as the slide bar 24 actuated from its cam through the intervention of the pawl 18 or equivalent connection, the said bar can be released when the machine is stopped, so that the clamp jaws may be open to permit free manipulation of the mattress on the table, even if the machine is stopped with the cam roller 15 on the high part of the cam 10 which is the position to close the clamp in the operation of the machine.

The feed clamp 3, 3, and actuating mechanism thus far described by which it is given its opening and backward, followed by its closing and forward movements, constitute the feed mechanism proper and serve to advance the mattress properly, step by step in the intervals between successive cycles of operation of the stitcher by which the knotted loop individual stitches are produced, but in order to relieve said feed mechanism of the drag of the mattress on the table and facilitate the movement of the mattress over the table an auxiliary appliance is provided which will now be described.

A number of belts 40, best shown in Figs. 1 and 2, are mounted on pulleys 41 fixed on shafts 42 mounted in bearings below the table at right angles to the direction of feed of the mattress, with the periphery of the pulleys extending through openings in the table so that the upper stretches of the belts lie on the top of the table between it and the mattress as shown in Fig. 2, and are parallel with the direction of feed. The auxiliary feed belts are preferably made of fabric or material having more frictional hold on the mattress than the table top so as to carry the mattress along with them when moving although they will not interfere materially with the movement of the mattress in the manipulation by the operator in placing it in position to begin stitching, or in turning it when the end of the side being stitched is reached.

In order to contribute to the feed operation after the mattress has been properly positioned in the feed clamp 3, 3 the belts 40

are moved an amount corresponding to the feed at the same time and speed as the feed clamp in its forward movement as follows.

One of the shafts 42 has fixed upon it a ratchet wheel 43 (see Fig. 9) adapted to be acted upon by a pawl 44 on a carrier 45 loosely mounted on said shaft and connected with a link 46 extending to and connected with a crank arm 47 on the rock shaft 7 which operates the lower jaw of the feed clamp in its forward and backward movements. Thus in the forward feed movement of the feed clamp, effected as above described, the pawl 44 rotates the belt shaft 42 and causes the auxiliary feed belts 40 to travel in unison with said clamp, and said belts carry the body of the mattress lying upon them along in unison with the part gripped by the feed clamp without any drag on said clamp, and in the backward movement of the open feed clamp the pawl 44 turns back over the ratchet wheel 43 without affecting the belts and mattress thereon.

In order to facilitate the handing of the mattress by the operator as in running it back after one side has been stitched preparatory to turning and positioning it for stitching the next side, the belt shaft 42 is connected, as by sprockets and chain 48, with a shaft 210 in line with, but normally disconnected from, the power shaft 21 (see Fig. 3) and a clutch 49 is provided which enables the operator at will to connect shaft 210 with the driving shaft 21 causing the feed belts 40 to be run in the backward direction at a sufficient speed to carry the mattress back rapidly to position for beginning the stitching.

The pawl 44 is disengaged from the ratchet wheel 43 before the clutch 49 is engaged, and the cam shaft of the stitcher and the actuating cam of the feed mechanism are disengaged from the main shaft 20 at this time, provision of any suitable or usual kind being made by which the engagement may be effected so that the feed mechanism may be operated while the stitcher is not running, and the stitcher may then be brought into operation in proper timing relative to the feed.

The mattress is guided and positioned or gaged relative to the stitching instrumentalities by a pair of guide bars 50 which bear on the top and bottom surfaces of the mattress as near as practicable to the place of action of the stitcher mechanism as shown in Fig. 2 and thus gage the upper and lower surfaces of the mattress relative to said mechanism, said bars bearing on the mattress for a considerable distance parallel with the edge being stitched both in advance of and beyond the point at which the stitching takes place as appears in Fig. 4.

The said guide bars are pivotally sup-

ported at their rear ends, that is, beyond or past the stitching point, on the rock shafts 6, 7, of the feed mechanism proper, and at their forward ends they are curved 5 so as to afford a flaring entrance for the portion of the mattress coming into the space between said guide bars as the stitching progresses.

The outer ends of the bars 50 are connected with hangers shown as shafts 52, 53, carried by frames or radius arms 54 pivotally supported on the rock shafts 6, 7, and the upper shaft 52 is connected by a rod 55 with a crank arm 56 on a rock shaft 57 having an opposite crank 58 connected by a rod 59 with the shaft 53 of the support for the lower guide bar.

A spring 60 acting on a short arm connected with said rock shaft 57 tends to turn 20 the same in the direction to move the lower bar 50 upward and the upper bar downward and thus to cause said bars to be pressed firmly but yieldingly against the mattress between them, while an opposite arm of 25 said rock shaft 57 is connected by a link 61 with a treadle 62 by depressing which the operator can separate the guide bars 50 widely so as to release the mattress or permit one to be adjusted in position relative 30 to the stitcher mechanism by the operator who stands at the left of the stitcher mechanism as seen in Fig. 1 where the mattress can be manipulated conveniently to position 35 it at the beginning of the stitching of each side in which the feed is from left to right.

Owing to the recess 22 in the table the mattress is supported and held in the vicinity of the stitcher mechanism solely by the feed jaws 3, 3 and the guide bars or 40 clamp 50, 50 which press equally but yieldingly against the top and bottom of the mattress so that any slight variation in vertical thickness is distributed equally at top and bottom instead of appearing wholly at the 45 top as would be the case if the mattress was supported on the table at the stitching point, and said feed and guide clamps hold the mattress in advance of and beyond the stitching devices sufficiently to control it at the beginning and end of a seam.

It sometimes happens that the side of the mattress is not quite square so that the upper and lower corners instead of being in a vertical line as shown at the right and left 55 hand in Fig. 2 upon arriving at the stitching point tend to stand a little out of vertical alinement which if not corrected might make the upper and lower edge rolls somewhat unequal, to the detriment of the appearance of the work.

The squaring or regulation of the mattress when such correction is required is performed by the regulating awls 70 and their actuating mechanism the relation of which 60 to the stitcher mechanism is best shown in

Fig. 2 and the details of which are shown in Figs. 6, 7, and 8.

The said awls 70, one for each corner of the mattress, are fixed in the stocks 71 which are pivotally mounted in a carrier 72 on a slide 73 mounted in guides 74 in which it is movable in the direction to cause the awls, when in normal position in the carrier as shown in Fig. 6, to penetrate the side of the mattress, the upper awl between the middle 75 and the upper corner, and the lower awl in like relation to the lower corner of the mattress as will be understood from Fig. 2.

The slide 73 is actuated in its movement towards and from the mattress by another slide 75 similarly movable in the guides at 80 74 and having affixed to it a block or angle plate 76 which extends over the top of the carrier slide 73 and is connected by a link 77 with a lever 78 fulcrumed at 79 on the frame and having a cam roller in engagement with the groove of a cam 80 timed relative to the feed cam 10 to cause the awls to perform their action on the mattress in the 85 interval between successive feed movements thereof.

The slide 75 is connected with the slide 73 to actuate it in the forward or penetrating movement of the awls by a latch or hook 81 pivoted at 82 on the block 76 and acted upon by a spring 83 which tends to turn it into engagement with a projection 84 from the slide 73 and thus to lock the two slides together when they are in the normal position 90 with the awls withdrawn from the mattress as shown in Fig. 2.

Thus when the slide 75 advances towards the mattress it carries the slide 73 with it until the awls have penetrated for their entire length as indicated in Fig. 10 at which point a trip cam 85 acting on a pin 86 on the latch 81 disengages the latter from the projection 84 after which the slide 75 may continue to advance without producing any further longitudinal or penetrating movement of the awls, in which advance it actuates the awls in the pivotal movement 105 which will now be described.

The pivoted awl stocks are each provided with a cam arm 90 and are acted on by springs 91 which keep said arms 90 against an actuating surface on a plate 92 on the end of the slide 75, and when said slide is latched to the slide 73 as shown in Figs. 2 and 6 the said awls are retained in line with the slides. As soon as the penetrating movement is completed and the latch 81 has been tripped the slide 75 continues its advancing movement and by plate 92 acts on the cam arms 90 and thus rotates the awl stocks 71 and causes the awls to swing or move laterally towards the corners of the mattress as indicated by the dotted lines in Fig. 6.

It has been found desirable to have the axes of the awl stocks inclined as shown so 130

that in the pivotal movement the awls not only swing upward and downward respectively but both swing forward in the direction of the feed of the mattress as appears in the plan view, Fig. 7, in which the slide 75 is shown as having completed its movement relative to the slide 73 from the position shown in Fig. 6, in which the latch 81 is about to be disengaged from the projection 84 to release the slide 73.

In the return movement of the actuating slide 75 the cam plate 92 first recedes, permitting the springs to act to swing the awls back into line, and then the block 76 engages the projection 84 and carries the slide 73 along with the slide 75 and withdraws the awls to the normal position shown in Fig. 2, the latch 81 at the same time engaging the projection 84 preparatory for the next cycle 20 of operation of the regulating awls.

The action of the awls in squaring the mattress when necessary is illustrated in Figs. 10 and 11. If either corner falls away from vertical alinement with the other as indicated at the lower corner in Fig. 10, the corresponding awl will find the stuffing material more dense between it and the side fabric, and in its movement downward and outward (toward the right in Fig. 10) and 30 forward in the direction of the feed it will force the stuffing and covering fabric outward and bring it into vertical alinement with the other corner as shown in Fig. 11. Whether the mattress requires such adjustment or not, the awls insure that the stuffing shall properly fill the fabric at the corners before arriving at the point where the stitch is made, thus contributing to the uniformity of the upper and lower roll-edges.

40 The operation is as follows:—

The stitcher is stopped with the needles out of the material, and with the pawl 18 disengaged from the bar 24 and consequently with the feed jaws 3, 3 widely separated, and 45 the operator by depressing the treadle 62 also separates the guide rails 50, 50 so that the mattress may be moved freely between them. The mattress is then placed by the operator with its side in proper relation to 50 the stitcher mechanism, the auxiliary feed belts 40 being run backward to assist in this operation if desired.

The treadle 62 is then released causing the 55 guide rails to clamp the mattress yieldingly between them and the machine is started. The pawl 18 engages the bar 24 and the feed mechanism is set in operation, the jaws 3, 3 clamping the mattress and, assisted by the belts 40, 40 carrying it forward under 60 the guidance of the rails 50, 50 through which it slips, and then holding it while a cycle of operations of the stitcher is performed, at the end of which the jaws 3, 3 move apart, then move back, and then close 65 upon the mattress and move forward again

and the operations just described are repeated until one side of the mattress is stitched.

The machine is then stopped and the mattress released from the feed and guide members as at the start, and the mattress is run back by the belts 40, 40 and turned quarter around on the table and again adjusted to the stitcher after which the next side of the mattress is stitched, and so on until all four 75 sides have been completed.

The regulating awls 70, 70 act to adjust the side of the mattress by giving uniformity to the stuffing at upper and lower corners, their operation being performed in the intervals between the feed steps while the stitching cycle is being performed, and acting at a point in advance of the stitcher so as to prepare the mattress for the action of the stitcher.

Some portions of this invention are applicable to, and might be embodied in a machine which acted upon only one corner or edge of the mattress at a time, and some portions or features of the feed mechanism 90 might be combined with other than roll edge side stitching instrumentalities.

I claim:—

1. The combination with a mattress supporting table and stitcher mechanism located at one side thereof, of a pair of feed members adapted to clamp the mattress between them, and actuating mechanism whereby the said feed members advance the mattress along the said table past the 95 stitcher mechanism.

2. A mattress supporting table and feed mechanism adapted to engage the mattress and feed it along the table, combined with auxiliary feed belts having stretches on said 100 table parallel with the direction of feed, and actuating mechanism whereby said belts are moved in unison with the feed mechanism in the direction of the feed.

3. A supporting table and feed mechanism 110 for moving a mattress along the same, combined with feed belts and means for moving the same in unison with the feed mechanism, and independent means for moving said belts continuously in the reverse direction.

4. A mattress supporting table and stitcher mechanism located at one side thereof, combined with feed mechanism for feeding the mattress along the table relative 115 to the said stitcher mechanism, and a pair of guide bars adapted to bear on the top and bottom surfaces of the mattress on lines adjacent to the point of action of the stitcher mechanism and parallel with the direction 120 of feed, the said table having a recess in which the lower guide bar has access to the bottom of the mattress.

5. A mattress support and stitcher mechanism adapted to operate upon the upper 130

and lower corners of the side of the mattress concurrently combined with regulating awls and means for forcing them endwise into the side of the mattress, and means swinging 5 said awls after penetration one towards the upper and the other towards the lower corner of the mattress.

6. A mattress support and stitcher mechanism adapted to stitch the upper and lower 10 corners of the side of the mattress concurrently, combined with regulating awls and an awl carrier with which said awls are pivotally connected and means for moving said awl carrier towards and from the side of 15 the mattress and means for rocking said awls on their pivotal connection with the said awl carrier, one towards the upper and the other towards the lower corner of the mattress.

20 7. A mattress support and stitcher mechanism adapted to stitch the upper and lower corners of one side of the mattress at the same time, combined with awls pertaining to the upper and lower corners respectively, 25 and an awl carrier with which said awls are pivotally connected each on an axis inclined relative to the lengthwise direction of the mattress side, and means for moving said awl carrier and awls towards and from the 30 side of the mattress, and means for rocking said awls on their inclined pivotal axes.

8. A mattress supporting table and stitcher mechanism located at one side thereof, said table having a recess in the portion 35 adjacent to said stitcher mechanism, combined with a pair of feed jaws adapted to clamp the portion of the mattress lying over said recess in the table, and a pair of rock shafts, one above and the other below the 40 level of the table, having cranks with which said feed jaws are pivotally connected, and means for moving said feed jaws on said pivotal connections towards and from one another to clamp and release the mattress 45 and means for oscillating said rock shafts to move said jaws simultaneously back and forth in the direction of feed.

9. A mattress supporting table having a recess in one side thereof and a stitcher 50 mechanism adapted to act on the portion of the side of a mattress lying over said recess, combined with feed mechanism and a pair of guide bars adapted to engage the portion of the mattress lying over said recess on 55 lines parallel with the direction of feed, and means for yieldingly pressing said bars towards one another to cause them to bear against the top and bottom of the mattress, and means under control of the operator for 60 moving said bars apart to release the mattress.

10. A mattress support and stitcher mechanism adapted to act upon the upper and lower corners of the mattress concurrently,

combined with regulating awls and an awl 65 carrier with which they are pivotally connected, and an actuator and means for engaging it with, and disengaging it from, the awl carrier, and means for effecting pivotal movement of the awls by the movement of 70 the actuator after disengagement from the awl carrier.

11. Mechanism for packing the stuffing of a mattress filled with fibrous material into 75 the edge of same, comprising an awl, means for thrusting said awl into the mattress transversely through one of the two complementary relatively angularly disposed tick parts which define said edge and means for effecting a pivotal movement of said awl 80 so as to move the point of said awl longitudinally of the edge of the mattress and also toward the other complementary tick part.

12. Mechanism for packing into the edge 85 of a mattress having upper and lower tick parts and a side tick part connecting the upper and lower tick parts and filled with fibrous material, a portion of said material, comprising a packing awl, means for thrusting said awl into one of said tick parts transversely at a point adjacent said edge and means for subsequently effecting a swinging movement of said awl to move the point of 90 said awl a substantial distance longitudinally of said edge and a substantial distance toward the said edge.

13. The same as claim 11 with a carrier 95 for the awl movable in the direction of said transverse movement and means for maintaining the awl on said carrier in alignment 100 with the said movement during its insertion.

14. Mattress - edge - filling-packing-mechanism comprising an awl-carrier, means for moving said awl-carrier toward a tick portion 105 of a mattress stuffed with fibrous material, an awl mounted on the forward end of said carrier and provided with means for maintaining itself substantially in alignment with the direction of movement of the carrier and means for rocking said awl on said carrier to cause the point of said awl to move longitudinally of the mattress edge and also toward the tick part which with 110 said first mentioned tick part defines said edge.

15. Mattress - edge - filling-packing-mechanism comprising an awl-carrier, means for moving said awl-carrier toward a tick portion 115 of a mattress stuffed with fibrous material, an awl mounted on the forward end of said carrier and provided with means for maintaining itself substantially in alignment with the direction of movement of the carrier and means for rocking said awl on said carrier to cause the point of said awl to move longitudinally of the mattress edge and also toward the tick part which with 120 said first mentioned tick part defines said 125

edge, said last named means comprising a pivot having its axis inclined with reference to the planes of both of said tick parts.

16. Mechanism for packing the stuffing of

- 5 a mattress filled with fibrous material into the edge of same, comprising an awl, means for thrusting said awl into the mattress transversely through one of the two complementary relatively angularly disposed
- 10 tick parts which define said edge and means for effecting a pivotal movement of said awl so as to move the point of said awl longitudinally of the edge of the mattress and also toward the other complementary
- 15 tick part, the arrangement including means resiliently tending to restore said awl to its entering position.

- 17. Mattress-edge-packing-means comprising a reciprocatory awl-carrier movable
- 20 transversely in a plane substantially parallel with the top and bottom surfaces of the mattress and in a direction transversely of the side surface, an awl normally positioned on said carrier with its axis parallel with
- 25 said line of movement and pivoted on said carrier on an axis which is inclined to said plane and also to the said side surface, means for maintaining said awl in said alignment during an advance movement of
- 30 said carrier thereby to cause the said awl to penetrate the side surface of said mattress

and means for rocking said awl on its pivot after the awl has penetrated into the mattress filling for a substantial distance.

18. Mattress-edge-packing-means comprising

- 35 a reciprocatory awl-carrier movable transversely in a plane substantially parallel with the top and bottom surfaces of the mattress and in a direction transversely of the side surface, an awl normally positioned
- 40 on said carrier with its axis parallel with said line of movement and pivoted on said carrier on an axis which is inclined to said plane and also to the said side surface, means for maintaining said awl in said
- 45 alignment during an advance movement of said carrier thereby to cause the said awl to penetrate the side surface of said mattress and means for rocking said awl on its
- 50 pivot after the awl has penetrated into the mattress filling for a substantial distance, and means resiliently tending to rock said awl back into its normal aligned position.

- 19. The same as claim 11 with means for effecting step-by-step movements of the mattress relative to said awl in a direction parallel with the edge of the mattress and corresponding with the direction of movement of the point of said awl longitudinally of
- 55 said edge.
